DESIGN FOR A DRESS ENSEMBLE

Margaret Michelson, New York, N. Y.

Application July 19, 1938, Serial No. 78,576

Term of patent 3½ years

To all whom it may concern:

Be it known that I, Margaret Michelson, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The characteristic feature of my design resides in the combination on the halter dress as shown of the specific skirt section having graduated, contrastingly colored appliqués arranged in the manner disclosed.

I claim:

The ornamental design for a dress ensemble, substantially as shown and described.

MARGARET MICHELS
